UNITED STATES PATENT OFFICE.

THOMAS D. LORING AND ALBION P. GILES, OF BOOTH BAY, ME., ASSIGNEES
TO THE KNICKERBOCKER ICE COMPANY, OF PHILADELPHIA, PA.

ICE-PLANER.

SPECIFICATION forming part of Letters Patent No. 329,400, dated October 27, 1885.

Application filed March 24, 1884. Serial No. 125,279. (No model.)

To all whom it may concern:

Be it known that we, THOMAS D. LORING and ALBION P. GILES, both citizens of the United States, and residents of Booth Bay, in 5 the county of Lincoln, State of Maine, have invented a new and useful Improvement in Ice-Planers, which improvement is fully set forth in the following specification and accompanying drawings, in which—

10 Figure 1 is a top or plan view of an ice-planer embodying our invention. Fig. 2 is a longitudinal vertical section thereof in line x x , Fig. 1.

Similar letters of reference indicate corresponding parts in the two figures.

15 Our invention consists of an ice-planer having planing blades or knives forming a cutter which is flaring in front, or where the ice is first received, whereby the blades rest on the 20 ice on opposite sides thereof, and are consequently held firmly to the work.

It also consists of an ice-planer having the frame which carries its planing blades or knives made vertically adjustable and provided with guides, whereby ice of different 25 sizes and shapes may pass under said frame without injury thereto.

It also consists of means for adapting the blades or knives to the removal of definite 30 quantities of snow or top ice.

Referring to the drawings, A represents an 35 inclined plane or frame, and B the conveyer for ice employed therewith, as well known. C represents a frame fitted to guides C', which rise from the frame A, the under side of said frame carrying the planing blades or cutters D, which extend parallel with the inclined portion of the plane or frame A. Connected with the frame are cords a, which are passed 40 around pulleys b, mounted on the guides C', the ends of the cords having weights c, whereby when the frame is raised it is assisted in its motions by said weights, the frame returning to its normal position by gravity, and serving 45 to hold the blades or cutters in contact with the ice passed upwardly on the plane or frame A beneath the frame C. At the lower end or front of the frame C is a guide, E, which is pivoted or hinged to said frame, and to said 50 guide is pivoted or hinged an apron, F, which

is V-shaped and located between the guide E and blades or cutters D, it being noticed that said blades or cutters are likewise V-shaped, and so disposed that they flare at their forward ends, whereby the ice is presented first 55 to said ends, and lastly to the point or angle of the blades or cutters. The guide E is vertically adjustable by means of screws G and nuts H, and the apron F is vertically adjustable by means of screws J and nuts K, it being 60 seen that the guide and apron may be moved vertically on their adjacent ends, so as to set the angle or upper end of the apron higher or lower relatively to the blades and cutters, whereby the latter are rendered adjustable for 65 planing to greater or less extent the snow or top ice from the block of ice. It will be seen that as the block of ice ascends the inclined plane it strikes the guide E, thus raising the frame C, whereby the weight of the latter is 70 superimposed on the block, and as the block advances it moves under the apron F, and is forced against the blades or cutters D, so that snow, top ice, dirt, &c., are removed from the block, and the latter is thereby nicely planed, 75 the snow, &c., dropping through the frames C A. The block continues its motion and passes the frame C, which latter then falls to its normal position, ready to be raised by the next advancing block. Owing to the guide E occupying an inclined position, it is adapted to admit under it blocks of ice of different sizes and shapes, whereby the frame C is readily raised by such blocks without injury. In order 80 to prevent rapid descent of the frame C after the block has passed the blades or cutters D, said frame C has secured to its upper end an inclined guard, K', which projects upwardly and bears against the passing block, thus causing an easy descent of the frame C. The blades 85 or cutters D are flaring toward the front of the frame C, as has been stated, whereby the front ends of both blades are simultaneously presented to and rested on the block of ice, so that the planing is uniform, and the blade or 90 cutter of either side is prevented from being strained upwardly, as both blades are uniformly and firmly held down to their work on the block of ice.

We do not lay claim, broadly, to an ice-cut- 100

ter having a rising and falling frame, to which a planing blade or cutter is attached, nor to an angular cutter flaring in front.

Having thus described our invention, what we claim as new, and desire to secure by Letters Patent, is—

1. An ice-planer having a rising and falling frame carrying planing blades or cutters, and a guide at the front of said frame, substantially as and for the purpose set forth.

2. An ice-planer having a rising and falling frame carrying planing blades or cutters, and a guard at the rear of said frame, substantially as and for the purpose set forth.

15 3. An ice-planer having a rising and falling frame carrying planing blades or cutters, and a guide and a guard at the front and rear of said frame, substantially as and for the purpose set forth.

20 4. An ice-planer provided with a vertically-adjustable apron in front of the planing blade or cutter, substantially as and for the purpose set forth.

5. An ice-planer provided with a rising and falling frame carrying a planing blade or cutter, and a vertically-adjustable guide at the front of said frame, substantially as and for the purpose set forth.

6. An ice-planer having a planing blade or cutter and a vertically-adjustable guide and 30 apron in front of said blade or cutter, the guide and cutter being pivoted or hinged together, substantially as and for the purpose set forth.

7. In an ice-planing machine, the guide E, hinged or pivoted to the frame C, in combination with the adjusting-screw G and nut H, substantially as described.

35 8. The V-shaped apron F, having the adjusting-screw J, with nut K, in combination with the adjustable guide E, substantially as 40 described.

THOMAS D. LORING.
ALBION P. GILES.
